UNITED STATES PATENT OFFICE

RICARDO BARRIES, OF SUSANVILLE, CALIFORNIA

EXHAUST DEFLECTOR FOR TRACTORS

Application filed June 16, 1927. Serial No. 199,286.

This invention relates to a new and useful device in the nature of an exhaust deflector particularly adapted for tractors, as a means of deflecting the exhaust gases from the motor 5 employed to operate the tractor.

The object of the invention is to provide an exhaust deflector of novel construction and arrangement of parts, hereinafter more fully described, claimed and illustrated in the accompanying drawing.

Fig. 1 is a front elevational view of my improved exhaust deflector.

Fig. 2 is a rear elevational view thereof.

Fig. 3 is a vertical central sectional view 15 illustrating a modification of my improved device.

Fig. 4 is a front elevational view illustrating a modification of my improved device.

Fig. 5 is a further development of my improved device.

As here embodied my improved device comprises a receptacle 10, of box shaped construction, having an open upper end, covered by a screen member 11, attached to a rim member 12, adapted to engage the sides of the above mentioned open upper end of the receptacle 10. The rear portion of the receptacle 10 is provided with an opening, having an outwardly flanged element 13, adapted to receive one extremity of the elbow member 14. The elbow member 14 is of the usual 90 degree type, and is adapted to engage in the extremity of the exhaust pipe 15 of the motor adapted to be used in a tractor. The extremity of the exhaust pipe 15 is somewhat enlarged, as at 16, so as to limit the engagement 25 of the elbow member 14. The clamping member 17, of ring shaped construction, is adapted to encircle the enlarged extremity 16, of the exhaust pipe 15, and is provided with apertures, at its extremities, adapted to receive the threaded member 18, a machine screw, bolt, or the like, and the usual nut 19, as a means of contracting the enlarged extremity 30 16 of the exhaust pipe 15, as a means of securing my improved device in place. A screen 20 is mounted within the receptacle 10 and arranged for assuming various inclined 45 positions.

50 The above described construction is such

as will permit the screen member 20 to function as a spark arrester, in event my improved device is attached to a comparatively short exhaust pipe. The above described construction is also such as will permit the receptacle 55 10, to deflect the exhaust gases upwardly, away from, or out of contact with the operator of the tractor to which same is attached.

I have shown the frame member 21, provided with elongated apertures 25, formed at the sides thereof, at or near its upper portion. The rod 26 is adapted to engage in the elongated apertures 25, and is secured to the sides of the receptacle 10, as a means of pivotally 60 and slidably mounting the screen member 20, in the receptacle 10. The rod 27 is pivotally attached, at its upper extremity as at 28, intermediate the screen member 20, and extends downwardly therefrom. The rod 27 is provided with a threaded lower portion 29, engaging in a threaded aperture formed in the adjusting member 30. The adjusting member 30 is provided with an enlarged head 31, positioned outside the bottom of the receptacle 65 10. The adjusting member 30 is rotatively mounted in the bracket 32, attached to the bottom of the receptacle 10. The collar 33 is attached to the adjusting member 30, as a means of holding the adjusting member 30 70 in place in the bracket 32.

The above described construction is such as will permit the screen member 20 to be positioned at any desired angle when the enlarged head 31 of the adjusting member 30 is 75 turned or rotated.

In Fig. 4 of the accompanying drawing, I have shown my improved device provided with an aperture at the bottom thereof, having an outwardly flanged portion 34, as a 80 means of directly attaching my improved device to the above mentioned exhaust pipe 15. The receptacle 10 is provided with a frustum conical top member 35. A screen member 36 is attached to one side of the receptacle 10. 85

In Fig. 5 of the accompanying drawing, I have shown a disc member 41, secured to the central portion of the screen member 11, which is provided with an aperture to accommodate the said disc member 41. A similar 90 100

disc member 42 is pivotally attached, at its center to the center of the disc member 41. The disc member 42, has formed therein radial elongated apertures 43, adapted to register with similar apertures 44 formed in the disc member 41. The above described construction is such as will permit the rate of flow, or discharge of the exhaust from the motor to be regulated, as may be desired.

Having thus described my invention what
10 I claim as new and desire to protect by
Letters Patent of the United States is as
follows:

15 1. An exhaust deflector of the class de-
scribed, comprising an exhaust receptacle
having an inlet opening and a top exhaust
opening, a deflector within the receptacle, and
extending across the inlet opening at an
inclination, a screen closing the said top ex-
haust opening, loop members formed at the
20 sides near the top of the deflector to pro-
vide elongated apertures, a rod engaged thru
the apertures and secured to the sides of the
receptacles, a second rod pivotally attached
at one of its ends to the said deflector, and
extending downwardly therefrom, an adjust-
ing member threadedly engaged to the bot-
25 tom of the said second rod, and means for
rotatively connecting the adjusting member
with one side of the receptacle.

30 2. An exhaust deflector of the class de-
scribed, comprising an exhaust receptacle
having an inlet opening and a top exhaust
opening, a deflector within the receptacle,
35 and extending across the inlet opening at
an inclination, a screen closing the said top ex-
haust opening, loop members formed at the
sides near the top of the deflector to pro-
vide elongated apertures, a rod engaged
40 thru the apertures and secured to the sides
of the receptacle, a second rod pivotally at-
tached at one of its ends to the said deflector,
and extending downwardly therefrom, an
adjusting member threadedly engaged to the
45 bottom of the said second rod, and means
for rotatively connecting the adjusting mem-
ber with one side of the receptacle, consist-
ing of a bracket attached to the receptacle,
the adjusting member being rotatively mount-
50 ed in the bracket, said adjusting member
also being formed with an enlarged head,
and a collar attached to the adjusting mem-
ber, and abutting the bracket.

In testimony whereof I have affixed my
55 signature.

RICARDO BARRIES.
